SANITARY GARTER BELT

Irving Kaldor, San Francisco, Calif.

Application April 26, 1947, Serial No. 744,223

2 Claims. (Cl. 2—304)

1

The invention, in general, relates to feminine wearing apparel of the foundation garment type, and more particularly relates to an improved garter belt affording the dual function of supporting hosiery and of providing means for ready attachment of sanitary napkins thereto.

As is perhaps well known, women heretofore have employed various individual belts or supporting devices, separate and apart from the conventional hosiery supporting means for the purpose of fastening a sanitary napkin in proper position and for maintaining the same in such position for intervals of time. Many of these prior belts or devices are, in the main, make-shift garments having somewhat unsatisfactory results when it comes to supporting a sanitary napkin properly for the time interval required. Often-times, these make-shift and other devices, being separate or independent from other garments normally worn by women, become lost and cannot be conveniently replaced. The present invention is directed to the provision of a dual purpose garment which can be worn normally at all times and which affords the belt for sanitary napkin always available.

A primary object of the invention is to provide an improved sanitary garter belt having incorporated therein the usual means for supporting hosiery as well as means for attaching a sanitary napkin thereto readily.

Another object of the present invention is to provide an improved sanitary garter belt of the indicated nature which is additionally characterized by its ability to retain a sanitary napkin on the body of the wearer in a proper position for desired intervals of time.

A still further object of my invention is to provide an improved sanitary garter belt of the aforementioned character which can easily and readily be manufactured and which lends itself readily to volume production at low cost.

Another object of the invention is to provide an improved sanitary garter belt of the indicated nature which can be used substantially indefinitely and affords a sanitary napkin support always available with a standard garment.

The foregoing and other objects are attained in a preferred embodiment of my invention which is illustrated in the accompanying drawings. It is to be understood that I am not to be limited to the precise embodiment shown, nor to the precise arrangement of the various parts thereof, as my invention, as defined in the appended claims can be embodied in a plurality and variety of forms.

2

Referring to the drawings:

Figure 1 is a perspective view of a preferred embodiment of the invention.

Figure 2 is a development of the embodiment illustrated in Figure 1.

Figure 3 is an enlarged fragmentary detail illustrating the manner of forming the pockets for the napkin retaining elements.

Figure 4 is a sectional view taken on the line 10 4—4 of Figure 3.

Figure 5 is a view taken on the section line 5—5 of Figure 3.

In its preferred form, the improved sanitary garter belt of my invention preferably comprises 15 a front cloth section including depending elastic strips with garter buckles thereon, a rear cloth section permanently joined to said front section through the medium of elastic webbing; said rear section including depending elastic strips with 20 garter buckles thereon, together with pockets on the inner sides of said sections, short elastic strips secured within said pockets and projecting therefrom, and fasteners on said short elastic strips for enabling the attachment of a sanitary napkin 25 thereto.

As particularly illustrated in Figures 2, 3 and 5 of the annexed drawings, I provide a pair of cloth sections including a front section 11 which preferably is reinforced by seams 12 at all edges 30 and which is provided at one side thereof with a plurality of hooks 13, in the customary manner, whereby the front section 11 may be detachably fastened to the rear cloth section 16 through the medium of a relatively short elastic webbing section 17 having a plurality of cooperating eyelets formed therein, as indicated by the reference numeral 18. The two sections 11 and 16 are conveniently permanently joined together by a short elastic webbing 19 which is stitched to adjacent 35 lateral extremities of the two sections. Rear section 16 also is hemmed, as indicated at 20, on all edges to insure a relatively strong, durable garment. Each of the two cloth sections 11 and 16 is provided with conventional elastic strips, arranged in pairs at the lower lateral extremities 40 of each section as indicated by the reference numerals 21 and 22 on the front section and the reference numerals 23 and 24 on the rear section, 45 which carry standard garter buckles 25 so that the hosiery of the wearer of the belt can be conveniently and readily attached thereto. These elastic strips 21 to 24 inclusive are all stitched to the front and rear sections and each is provided with an adjustment link 26 to afford 50 55

shortening or lengthening thereof whenever desired.

In accordance with my invention, my improved sanitary garter belt is provided with means for readily attaching and for maintaining a sanitary napkin in proper position on the body of the wearer of my improved belt. To this end, I provide a pocket 27 on the inside of front section 11 and a pocket 28 on the inner side of rear section 16, the pockets 27 and 28 being disposed approximately at the longitudinal centers of the front and rear sections 11 and 16 as clearly illustrated in Figure 2 of the drawings.

Each of the pockets 27 and 28 is preferably formed by stitching a sheet 31 of soft material, such as sheeting bounded at the sides with hems 32, to the inside of the front and back sections 11 and 16, respectively, of the belt. Preferably, the sheets of sheeting 31 are stiffened longitudinally at their transverse centers with stays 33 which are confined within narrow pockets 34 formed on the inner side of the sheets 31 by a covering 35. Means for enabling the ready attachment and detachment of a sanitary napkin, not shown, in proper position on the body of the wearer of the belt preferably are confined within the pockets 27 and 28 and conveniently include strips 36 of elastic sewed to the upper inner edges of the sheets 31 and thus freely depend from such upper edges. A looped tab 37 of cloth is stitched to the free lower ends 38 of the elastic strips 36, and a safety pin, clasp or other fastening element 39 is carried by each of the tabs 37. Whenever it is desired to use a sanitary napkin, it is only necessary for the wearer of my improved garter belt to unclasp the safety pins, clasps, or other fastening elements carried on tabs 37, insert the pins, clasp or other fastening elements through the ends of a sanitary napkin after first placing the napkin in proper position, and then reclasp the safety pins, clasps or other fastening elements to properly secure the napkin to the belt. When not in use, the safety pins, clasps or other fastening elements remain clasped to and on the lower free ends of the tabs 37. Both of the pockets 27 and 28 are of approximately the full depths of the sections 11 and 16 and since the latter section is deeper or wider than the front section 11, the pocket 28 as well as the reinforcing stays 33, the narrow pocket 34 and the elastic strips 36 of such pocket 28 are longer than the corresponding pocket 27, stays 33, small pocket 34 and elastic strips 36 of the pocket 27 of the front section 11.

It is clear from the foregoing description and the views of the annexed drawings that I have provided an improved garter belt which not only accomplishes the normal and desirable function of snugly fitting the body of the wearer with ef-

fective hosiery support but also affords a readily available means for enabling quick attachment and detachment of a sanitary napkin thereto in effective operative position on the body of the wearer. This dual function sanitary garter belt obviates the necessity of a separate belt for sanitary napkins, affords always available fastening elements and belt for securing the sanitary napkin in position, and eliminates much time heretofore lost in attempting to locate safety pins and separate sanitary napkin belts. It is also clear that the safety pins, clasps or other fastening elements carried by the tabs 37 of the elastic strips 36 are not exposed to scratch or chafe the body of the wearer of my improved belt since the elastic strips 36 draw the safety pins, clasps or other fastening elements within the pockets 27 and 28 when not in use.

It is to be understood that the appended claims are to be accorded a range of equivalents commensurate in scope with the advance made over the prior art.

I claim:

1. A sanitary garter belt comprising a front cloth section, a rear cloth section connected to said front section, a first sheet of cloth stitched to the inner side of said front section to define a first open-bottom pocket on the inside and at the approximate longitudinal center of said front section, a second sheet of cloth stitched to the inner side of said rear section to define a second pocket having an open bottom on the inner side and at the approximately longitudinal center of said rear section; said first and second pockets being in alignment when the garment is worn on the body, an elastic strip within said first pocket and stitched at one end to the upper edge of said first sheet to depend therefrom, an elastic strip secured to the upper edge of said second sheet within said second pocket to depend from said second sheet, and napkin fasteners on the depending ends of said strips.

2. A sanitary garment belt as defined in claim 1, and including stays stitched to said sheets within said pockets for stiffening the garment against dislodgment when said strips are extended to fasten a napkin in position.
